UNITED STATES PATENT OFFICE.

WILLIAM M. WAY, OF COALINGA, CALIFORNIA.

PLIERS.

Application filed November 20, 1922. Serial No. 602,093.

To all whom it may concern:

Be it known that I, WILLIAM M. WAY, a citizen of the United States, residing at Coalinga, in the county of Fresno and State 5 of California, have invented certain new and useful Improvements in Pliers; and I do declare the following to be a full, clear, and exact description of the invention, such as will enable others skilled in the art 10 to which it appertains to make and use the same.

This invention relates to improved pliers and it has for its principal object to generally improve upon tools of this class by providing one embodying crossed handles which are connected together by unique means broadly referred to as a double fulcrum and connection, the same embodying spaced pins extending through elongated 20 slots in a manner to permit the jaws to be spread a greater distance apart than would be permitted by a single immovable or adjustable pivot such as is commonly employed

Another and important object of the invention is to provide a connection of the aforesaid type which insures rigidity of construction and a very effective grip of the jaws on the object being acted on, the connection in its preferred construction 25 embodying a pin carried by and movable with each jaw and extending slidably through a slot on the other jaw, this arrangement assuring an equal distribution of strain on the parts.

Other objects and advantages of the invention will be apparent during the course 30 of the following description.

In the accompanying drawings forming a part of this specification and in which like 35 numerals are employed to designate like parts throughout the same:

Figure 1 is a side elevational view of a tool constructed in accordance with this invention showing the jaws spread apart to 40 an intermediate position.

Figure 2 is a top plan view of the tool.

Figure 3 is an elevational view of the outer end of the tool showing the jaws closed and the relation of the connecting 45 pins at this time.

Figure 4 is a longitudinal detail section taken on the line 4-4 of Fig. 3.

Referring to the drawings by numerals, 50 1 and 2 designate a pair of crossed handles which are provided at their outer ends with integral jaws 3. It may be noted that the

portions of the handles which cross one another are increased in width considerably to accommodate the unique double fulcrum and connecting means.

Although the last named means could be of some other construction, it by preference comprises a pair of elongated slots 4, one being formed in the widened portion of each jaw and these slots being arranged in divergent relation. In addition to the handles being equipped with the slots, each one is formed with a comparatively small opening 5 through which a connecting and pivot pin 6 extends. The small opening on one handle registers with the elongated slot on the other handle. Hence, the pin which extends through the opening also extends through the registered slot. One end of each pin is threaded and a nut 7 is arranged thereon to connect the handles together.

Normally, when the jaws are closed as seen in Fig. 3, the then adjacent ends of the slots register with one another and the pin 80 and small openings through which they extend are disposed at the opposite or remote ends of the slots. Now, by grasping the handles and moving them apart, it is obvious that the pins will engage the longitudinal edges of the slots and will be moved toward the opposite outer ends thereof as disclosed in Fig. 1. When the jaws are spread their maximum distance, the pins 85 will have moved close together and will be seated in the last named ends of the slots. Hence, when the jaws are engaged with an object, the strain will be distributed equally 90

to the two connecting pins. Consequently, a much stronger construction is provided 95 than is had with the single pin and slot connection commonly used. In this connection it may be stated that the present invention is vastly different from the type of connection just mentioned for in order to obtain the additional adjustment of the jaws with the usual slip joint, the connecting and pivot pin must be moved manually from one end of the slot to the other and with this arrangement when the pin is at one end of the slot, the jaws do not come into direct engagement with one another. With my arrangement, the pin does not remain at one end of the slot when the handles are 100

spread, but the two pins automatically and simultaneously move from one end of the slots to the opposite ends the moment the 105

handles are spread and this allows for the additional adjustment. Particular emphasis is therefore to be laid on this new method of operation for accomplishing the result 5 sought.

Attention is here directed to the fact that the present application is a "continuation in part" of an application for pliers filed by me on August 25, 1921, the same having 10 been designated by the Serial No. 495,230, but having been abandoned in view of the present improved construction.

By carefully considering the description 15 in connection with the drawings, persons familiar with devices of this class will doubtless be able to obtain a clear understanding of the invention. Therefore a more lengthy and detailed description is deemed unnecessary.

20 Since probably the best results may be obtained with the construction and arrangement herein shown and described, this is taken as the preferred embodiment of the invention. However, I wish it to be understood 25 that minor changes coming within the scope of the invention as claimed may be resorted to if desired.

I claim:

1. Connecting means for the handles of a 30 tool of the type specified embodying a pin carried by and movable with one handle and extending slidably through a slot in the other handle, said pin being disposed at one end of the slot when the jaws are in engagement with one another and being automatically moved to the opposite end of the slot as 35 the handles are spread apart, whereby to permit additional adjustment of the jaws to be had.

40 2. Connecting means for the crossed handles of pliers comprising a pair of pins extending through and automatically slidable in elongated slots when the handles are moved toward and from each other.

45 3. The structure as set forth in claim 2, wherein said slots are inclined with respect to one another.

50 4. Pliers comprising a pair of crossed handles having jaws at their outer ends, the crossed portions of the handles being equipped with relatively inclined slots, and pins extending slidably through the slots for connecting the handles together, said pins being movable automatically from end to 55 end of the slots when the handles are actuated.

5. A tool of the class described comprising a pair of crossed handles having jaws at their outer ends, and means associated with the overlapping portion of the handles for pivotally connecting them together, 60 said means embodying a pin carried by one handle and extending through an elongated slot formed in the other handle, said pin being movable from end to end of the slot 65 and being disposed at one end of the slot when the jaws are together and being automatically moved to the opposite end when the handles are actuated.

6. A tool of the class described comprising a pair of crossed handles, the overlapping portion of each handle being equipped with spaced openings, the openings in one handle registering with the openings in the other handle and pins passing through and 70 slidable in two of the openings when the handles are actuated.

7. A tool of the type specified comprising a pair of crossed handles, the crossed portions of said handles being equipped with 75 small unregistered openings and elongated slots, the adjacent ends of the slots registering when the handles are together, and connecting means extending through the small 80 openings and slots and slidable in the latter 85 when the handles are actuated.

8. A tool of the class described comprising a pair of crossed handles, the crossed portions of each handle being equipped with a slot, the two slots being disposed in divergent relation with respect to one another, and the adjacent ends thereof registering 90 with one another when the handles are close together, and pins carried by said crossed portions and extending through said slots. 95

9. A tool of the class described comprising a pair of crossed handles, the crossed portions of the handles being widened and each portion being equipped with a relatively small opening and elongated slot, the 100 slots of the respective handles being disposed in divergent relation, and connecting and pivot pins passing through the small openings in one handle and through the slots in the other handle, said pins being disposed at the remote ends of the slots when the handles are together but being automatically moved to the opposite ends of the slots when the handles are spread apart.

In testimony whereof I have hereunto 110 affixed my signature.

WILLIAM M. WAY.
